UNITED STATES PATENT OFFICE.

P. HILBERT MARTINSON, OF WENATCHEE, WASHINGTON.

FLY BOOK.

Application filed March 31, 1925. Serial No. 19,712.

This invention relates to improvements in fly-books, and has for an important object thereof the construction of a fly-book in which provision is made for the reception of 5 all of the small parts of the tackle employed in fly-fishing.

A further and more important object of the invention is to provide a fly-book having pockets for receiving lines and the like, the 10 outer surface of the pockets being of soft woolly material in which the barbs of the fly-hooks can be embedded for storage and are readily removable.

A further object of the invention is to 15 provide means whereby the gut leaders employed in fly-fishing may be coiled for storage, the mounting being such that the leader is removable without uncoiling the same, thereby permitting the leader to be soaked 20 before such uncoiling as it should be.

A still further object of the invention is to provide a device of this character which is readily and cheaply produced and which accordingly can be placed upon the market 25 at a relatively low cost.

These and other objects I attain by the construction shown in the accompanying drawings, wherein for the purpose of illustration is shown a preferred embodiment of 30 my invention and wherein:—

Figure 1 is a perspective view of a tackle-book, constructed in accordance with my invention, in the open position;

Figure 2 is a longitudinal sectional view 35 therethrough in the open position;

Figure 3 is a perspective view of the tackle-book closed.

Referring now more particularly to the drawings, the numeral 10 indicates a backing sheet preferably formed of soft leather or similar material. Secured to one face of the backing sheet and extending transversely thereof are pocket forming strips 11, 12 and 13, each of which is secured to the 40 backing strip 10 by stitching 14 securing its end edges and one side edge to the backing strip. The strips 11 and 12 are arranged next adjacent one another, the strip 11 being at one end edge of the backing strip and having its attached side edge coinciding with such end edge. The strip 12 has that side edge attached which lies next adjacent the strip 11, and the strip 13 has that side edge attached which lies next adjacent the strip 12.

The strips 11 and 12 are preferably

formed of clipped sheepskin having the woolly side thereof arranged outermost. In any event, the material of the strip will have upon its outer surface a woolly covering 60 in which the barbs of fly-hooks 16 may be engaged. The transverse width of the backing strip, and accordingly the length of the strips 11 and 12, is slightly greater than the length of the snells 17 applied to 65 these hooks, so that these snells may be straight when the hooks are in position as shown. At least one of the pockets 11^a and 12^a, formed between the strips 11 and 12 and the backing sheet 10, has a snap fastening 70 engagement, as at 18, with the backing sheet so that the pocket may be secured in closed position. The sheet 13 is further secured to the backing sheet by a row of stitching 19 extending transversely of the strip 13 75 at the approximate center thereof. Secured to the strip 13 and backing sheet is the male member 20 of a snap fastener, this being located at approximately the longitudinal center of the strip 13. A disk 21 is provided, 80 the inner face of which is provided with a layer of the woolly material, as indicated at 22, and the outer face of which is preferably reinforced by a disk 23 of the material from which the backing sheet 10 is 85 formed, this being secured to the disk 21 by stitching 24. The center of this arrangement is provided with the female member 25 of the snap fastener so that this disk may be detachably engaged in the book with its 90 inner woolly face opposing the outer face of the strip 13. The line of stitching 19 divides the space between the strip 13 and backing sheet 10 into a pair of small pockets 26. The unattached edge of the strip 13 is preferably spaced considerably from the adjacent edge of the backing strip 10 to thereby provide a flap 27. In folding the book, the strip 11 is folded against the face of the strip 12, then the book again folded and 100 the flap 27 secured to the body of the sheet 10 by snap fasteners 28.

In use the soft woolly material prevents any rasping action upon the snells 17 of the hooks 16 and further affords an excellent 105 material for securing the hooks in position within the book. Leaders may be coiled about beneath the disk 21 and by their friction against the woolly surface will be held in position. When it is desired to remove 110 the leaders, it is simply necessary to disengage the sections of the snap fastener when

the coil leaders may be removed and soaked before any attempt is made to straighten them. It will, of course, be understood that the pockets 11^a, 12^a and 26 will receive the remaining small portions of the tackle.

I claim:—

1. In a fly-book comprising a transversely foldable backing sheet, a plurality of strips of material of the same width as the backing sheet secured to said backing sheet and extending transversely thereof upon one side of the backing sheet, said strips of material being secured to the backing sheet at their ends and one side to thereby combine with the backing sheet to produce pockets, the outer faces of said strips of material being provided with a layer of fibrous material for the reception of barbs of hooks,

a pair of said layers opposing their fibrous faces during folding of the backing sheet. 20

2. A hook-book comprising a flexible folding backing sheet and a plurality of strips of clipped sheepskin extending transversely of the backing strip and each secured thereto at their ends and along one side, the woolly 25 faces of two strips opposing in the folded position of the backing strip.

3. In a hook-book, a backing strip and a disk detachably secured to the backing strip at its center, the surface of the disk next adjacent the backing strip being provided with a woolly covering. 30

In testimony whereof I hereunto affix my signature.

P. HILBERT MARTINSON.
